UNITED STATES PATENT OFFICE.

JOHN JUDD, OF NORTH PERTH, WESTERN AUSTRALIA, AUSTRALIA.

ROTARY INTERNAL-COMBUSTION ENGINE.

1,199,563.

Specification of Letters Patent. Patented Sept. 26, 1916.

Application filed March 16, 1915. Serial No. 14,750.

To all whom it may concern:

Be it known that I, JOHN JUDD, a subject of the King of Great Britain, and residing at Hart avenue, North Perth, Western Australia, Commonwealth of Australia, have invented certain new and useful Improvements in Rotary Internal-Combustion Engines, of which the following is a specification.

10 This invention relates to rotary internal combustion engines of the type wherein any number of radial cylinders rotate around a fixed crank shaft and the object of the invention is to provide an engine of such 15 rotating cylinder type which is not subjected to undue centrifugal strain and one which provides a highly efficient and self contained compact power motor adapted chiefly for industrial purposes.

20 This engine works on the four cycle principle and any number of cylinders may be employed; said engine being fitted with starting gear, carburetor, ignition means and other adjuncts which are ordinarily employed with internal combustion engines but for sake of clearness in description said adjuncts are not all shown or described.

Among other features of the invention one essential feature resides in the use of a 30 peculiar timing construction hereafter described which causes a regularity in performance of the functions of the exhaust valves so as to allow of the needful actions of exhaust and compression. These features will be explained in relation with a 35 five cylinder engine and with the aid of the attached drawings wherein—

Figure —1— is a transverse sectional view showing one cylinder as connected up 40 with the fixed crank shaft and related parts. Fig. —2— is a side elevation in which the timing construction is shown in section as on line $\alpha-\alpha$ of Fig. —1—.

Referring to said drawings “ a ” is the 45 cylinder of usual make and being one of five cylinders which are radially arranged for rotation around the fixed crank shaft “ a^1 ” said shaft being held in suitable bearings and secured to a base frame. In this 50 base frame may be placed the petrol or fuel chamber from whence the petrol is fed to the carburetor by force feed means or said chamber may be placed at a suitably high point so as to permit said fuel being fed by 55 gravity.

Each cylinder is provided with piston and

connecting rod “ a^2 ” and inlet and exhaust valves as “ a^3 ” and “ a^4 ” also spark plugs “ a^5 ” and contacts “ a^6 ”. The novel features of the invention will now be explained in their 60 relation with the construction of a five cylinder engine and in referring to the drawings “ b ” is a circular rotating distributing chamber for the petrol mixture and from said chamber “ b ” the induction pipe “ b^1 ” 65 connects with the cylinder “ a ” by way of the inlet valve “ a^3 ” as seen clearly in Fig. —1—. The said chamber b has a sleeve “ b^2 ” which acts as bearing for the crank shaft and said chamber is sealed by a fixed 70 flanged plate “ b^3 ” so as to effect a gas tight joint thereat during the rotation of the chamber “ b ” and said plate may be retained in position by a suitable spring.

The exhaust escapes by valve “ a^4 ” from 75 the cylinders “ a ” and into a peripheral hollow rim “ d ” shown broken away in Fig. —2— and from thence by pipe “ c ” into a hollow rotating chamber “ c^1 ” from whence as indicated by arrow it passes into the interior of a rim wheel “ c^2 ” and makes exit into the outer air through opening “ c^3 ” formed in the closure plate “ c^4 ” which latter fits neatly in the interior of rim “ c^2 ” as 80 seen in Fig. —1—.

The cylinders “ a ” may exhaust direct into chamber “ c^3 ” or said rim “ d ” may be divided up into cellular compartments corresponding in number to that of the cylinders employed and from each separate cell an exhaust pipe may lead to the chamber “ c^1 ” aforesaid. This peripheral rim “ d ” also acts as a reinforcement means and renders the engine as a whole rigid in construction and imparts ease of running and counteracts any 95 jar resultant from the working of the engine. Between said rim “ d ” and the crank shaft “ a^1 ” blades may be interposed to cause a current of air and act as cooling agents for the engine.

The invention further comprises a novel timing construction consisting of an outer rotatable crank case as “ e ” said case being five sided and agreeable with the five cylinders employed. In this case “ e ” is housed 105 the fixed cam “ f ” keyed on the shaft “ a^1 ” and having outstanding walls or ribs “ f^1 ”, see Fig. —2—, said ribs being concentric with the shaft “ a^1 ” while the cam path “ f^2 ” is an irregular eccentric thereto. In this 110 case “ e ” are mounted the pivoted and double armed levers numbered 1—2—3—4 and 5

and whose short arms "g" are adapted to engage against the ends of the tappet valve rods "g¹" and whereby the exhaust valves "a⁴" are operated. These rods "g¹" are provided with coiled springs "g²" for maintaining tension against the arms "g" while the other ends of said rods operatively engage with the pivoted lever "g³" for the opening of the exhaust valves "a⁴" in the well known manner. The lower ends of said rods "g¹" loosely slide through openings made in the case "e". On the long arms "j" of the levers are carried pins or rollers "j¹" which are adapted to alternately travel within the inner and outer paths or grooves "j²" and "j³" produced by the concentric rib "f¹" and eccentric cam path "f²". This timing construction consists of an escapement movement and referring to the position seen in Fig. —2— its operation is as follows:— The crank case "e" rotating with the engine as a whole in the direction of the arrow and upon one of the levers as "l" carried thereby meeting and engaging with the pivoted rocker gate "m" causes said lever "l" to travel within the inner path "j²" and said lever during its travel against said rocker "m" causes the latter to move to the position seen in dotted lines and which action, by the agency of finger "m¹" engaging with companion finger "m²" on the pivoted bridge "m³", causes said bridge "m³" to move to its inner position as shown by dotted lines thus allowing the following lever "2" to travel in the outer path "j³"; and by latter lever's resultant engagement against said bridge "m³" moves the latter to its outer position as seen in full lines and consequently causes the rocker "m" to resume its position as seen also in full lines and thus causing the next lever "3" to travel within the inner path "j²". The purpose of this alternate or escapement movement is to regulate the compression and exhaust functions of the exhaust valves "a" and thus produce the aforesaid four cycle principle of operations in each cylinder alternately. The exhaust valves communicate with and may be housed within the peripheral rim "d" and in which arrangement access doors are provided for cleaning or repair pur-

poses or said valves may be placed outside of said rim and arranged in a "side by side" manner or position with the inlet valves.

What I claim as my invention and desire to secure by Letters Patent is:—

1. In a rotary internal combustion engine of the character described, the combination of a fixed crank shaft disposed to have a series of cylinders rotate therearound, each cylinder having an exhaust valve and an inlet valve and a sparking means, a fixed timing cam plate for rendering the function of the exhaust valve of each cylinder regular, said plate having concentric ribs and eccentric cam grooves, said cam plate also having a rocker gate and a bridge pivotally mounted thereon, a case surrounding the said plate, concentric ribs and cam, levers pivotally mounted in the case and projecting from the latter and operated by the cam plate ribs and grooves, the levers having short arms, and a valve rod co-operating with the exhaust valve for regularly opening the latter, the one end of the said valve rod engaging the short arms of the levers at intervals. 70

2. In a rotary internal combustion engine of the character described, a stationary crank shaft, cylinders rotatably disposed with relation to said crank shaft, a rotary crank case, inlet and exhaust valves for the cylinders, the exhaust valves having valve rods operatively extending inwardly into the crank case, pivotally mounted double-armed levers held in the crank case and operative to engage the ends of the said valve rods, and a timing means associated around the crank shaft and consisting of a plate, a rocker and bridge both pivoted to the timing plate, and cam means and cam grooves co-operating with the said double-armed levers to cause the latter to effect an engagement with and operation of the said valve rods at regular intervals. 95

In testimony whereof I have hereto affixed my signature in presence of two witnesses.

JOHN JUDD.
